(57) **CLAIM**

The ornamental design for a clip holder for electronic devices as shown and described.

DESCRIPTION

1. Clip holder for electronic devices

1.1 : Perspective

1.2 : Back

1.3 : Front

1.4 : Left

Clip holder for attaching electronic devices, like phones, to a pocket of trousers, belts and clothes; fig. 1.1 is a perspective view from diagonal behind, fig. 1.2 is a back plan view, fig. 1.3 is a front plan view, fig. 1.4 is a side plan view; the short side at the back can be mounted on the electronic device or the case to which the electronic device is attached;

(Continued)

the long side of the holder facing the front is the part that remains outside and visible after the product is attached to the respective item.

1 Claim, 4 Drawing Sheets
